United States Patent Office

Des. 196,391
Patented Sept. 24, 1963

196,391

BOTTLE

Richard L. Platte, Ann Arbor, Mich., and Harry Marsh Sinclair, Port Clinton, Ohio; said Harry Marsh Sinclair assignor to The Sinclair Manufacturing Company, Toledo, Ohio, a partnership, and said Richard L. Platte assignor to The Dow Chemical Company, Midland, Mich., a corporation of Delaware

Filed Apr. 24, 1963, Ser. No. 74,600

Term of patent 14 years

(Cl. D58—8)

FIGURE 1 is a front elevational view of a bottle showing our new design;

FIGURE 2 is a side elevational view thereof;

FIGURE 3 is a top view thereof;

FIGURE 4 is a bottom view thereof;

FIGURE 5 is a cross-sectional view thereof taken along reference line 5—5 of FIGURE 1; and

FIGURE 6 is a cross-sectional view thereof taken along reference line 6—6 of FIGURE 1.

The rear and other side of the bottle not shown would appear the same, if illustrated, as the views shown in FIGURES 1 and 2.

We claim:

The ornamental design for a bottle, substantially as shown and described.
